LANDSCAPE PAVEMENT

Charles H. Rothmann, Closter, N. J.

Application April 30, 1938, Serial No. 205,341

1 Claim. (Cl. 94—2)

This invention relates to landscape pavement and has for one of its objects the production of a simple and efficient paving block especially designed for building roads, walks, streets, parks and special developments where hard paving is required.

A further object of this invention is the production of a simple and efficient paving block which is so designed as to provide a pocket between the adjoining blocks whereby the roots of seedlings may take root, and thereby provide an interlocking connection between adjoining blocks.

A further object of this invention is the production of a special format for producing a plastic block of a non-porous type possessing a maximum strength and a long life.

Other objects and advantages of this invention will appear throughout the following specification and claim.

20 In the drawing:

Figure 1 is a top plan view of a section of a roadway and the like, showing one form of design which may be produced by means of my improved paving block;

25 Figure 1a is a plan view showing a modified design arrangement of a herringbone type;

Figure 2 is an enlarged transverse sectional view taken on line 2—2 of Figure 1;

Figure 3 is a perspective view of the block of 30 the type shown in Figure 2;

Figure 4 is a transverse sectional view through a plurality of blocks showing a slightly modified type of block;

Figure 5 is a perspective view of one of the blocks 35 of the type illustrated in Figure 4;

Fig. 6 is a plan view of an assembly of a different type block;

Figure 7 is a transverse sectional view taken on line 7—7 of Figure 6; and

40 Figure 8 is a perspective view of the type of block shown in Figures 6 and 7.

By referring to the drawing, it will be seen that 45 10 designates the improved paving block which is preferably of an elongated type, being preferably slightly higher than its width, as shown in Figure 2. The block 10 is preferably formed of a special plastic material having a close texture and is preferably non-porous. The block 10 is provided along one of its longitudinal sides with a 50 longitudinally extending concave channel 11 and with a straight opposite side 12. The block 10 is also provided with a tread surface 13, and a base 14. The blocks 10 are preferably arranged in the manner shown in Figure 1, or in a manner shown 55 in Figure 1a, the blocks 10 fitting in adjoining

relation, as shown in Figure 2, wherein the concave face 11 of one block will face the straight face 12 of the adjoining block thereby providing a pocket 15 between the various blocks, which pockets 15 are filled with earth and in which seedlings, such as grass seedlings 16 may be planted, the roots of which may extend down into the pockets 15 in the manner shown in Figure 2, and provide an interlocking joint between the blocks 10 and at the same time provide a decorative effect 10 when the blocks are laid out in the pattern shown in Figures 1 and 1a, providing green grass borders around each block and producing an exceedingly attractive design formation. The concave faces 11 will provide pockets 15 which are relatively 15 restricted at their upper ends and broaden toward the center of the block allowing a wider space for the spreading of the roots of the seedlings, as well as the packing of the earth to provide an efficient interlocking joint between the blocks, in this way 20 tending to hold the blocks in firm anchored relation and allowing for a slight expansion and contraction at the same time under varying weather conditions.

Furthermore, it will be seen that the blocks may 25 be readily replaced for road repair, allowing the road to be maintained in excellent condition at all times, since the blocks will constitute replaceable units where new blocks may be readily substituted for worn or damaged ones without damaging the surface of the roadway, and also avoiding the difficulty of making a proper joint between 30 an old plastic structure and a new plastic formation.

As shown in Figures 1 and 1a, the blocks may be 35 arranged in various design formations, such as the regular checkerboard formation shown in Figure 1, and the herringbone formation shown in Figure 1a.

In Figures 4 and 5, I have shown a modified type 40 of the invention wherein a block 17 is illustrated, of a type similar to that shown in Figure 3 with the exception that the block 17 is provided with a longitudinally extending concave channel 18 upon each of its longitudinal side faces to provide 45 facing concave channels 18 upon the adjoining blocks when assembled in the manner shown in Figure 4, and providing a double convex pocket 19 between the blocks to receive the seedlings 20, such as the seedlings indicated by the numeral 50 16 and referred to above. As shown in Figure 4, the blocks 17 rest upon a foundation of soil, and it will be noted that the upper faces of the blocks are rounded or convex. The side edges of the blocks are also rounded and the highest point in 55

the upper face of each block is at the approximate center thereof to support traffic passing thereover away from the edges of the blocks and to prevent the blocks from tipping under the 5 weight of traffic passing thereover. In this manner, the seedlings growing between the blocks will be protected from becoming worn down by the traffic or choked by the tipping of the blocks. Furthermore, the blocks are spaced from each other, 10 as shown in Figure 4, both along their upper and lower edges thereby providing a moisture-feeding medium from above the blocks and also from the foundation soil below the blocks to the spaces between the blocks. In this manner the roots of 15 the seedlings may draw moisture from the soil below the blocks. The soil and roots of the seedlings between the blocks will also provide a tying medium to tightly hold the blocks together.

In Figures 6, 7 and 8, I have shown a further 20 type of block consisting preferably of a flat square block 21 which is adapted to be seated upon a porous mortar strip or layer 22 for holding the flat blocks 21 in place, the porous mortar or layer strip 22 resting upon a relatively deep layer of 25 sand 23. All of the blocks 13, 17 and 21 are formed of non-porous plastic material, but in the type shown in Figure 7, the porous layer 22 is provided for draining moisture away from the non-porous blocks 21 down through the sand base 23.

30 From the foregoing description it will be seen that a very simple and efficient paving block has been produced which may be formed in various designs without departing from the spirit of the invention, and these blocks may be molded in desired shapes in steel forms under pressure to produce a dense product. The block may be produced by an ordinary laborer and does not require special skill, and the blocks may be so shaped as may be required for special conditions.

40 I have found by actual experience that it is important that a very dense product be produced, and I, therefore, preferably construct my blocks by using the following formula: I first produce a semi-dry mixture, that is to say, a mixture which 45 is merely damp and is not wet, by using approximately one part cement, approximately three parts sand, approximately one part graded gravel, and approximately 18 per cent water. I place the product in a mold of suitable design, and place 50 the product under pressure, and then tamp the semi-dry mixture to extract all of the air from the material, and the interior of the mold, whereupon the molded product is removed and set out to thoroughly dry for about twenty-four hours, 55 and the blocks are then moistened or watered in

the usual manner for about three or four days, when they are then ready for use. By following this method, I have found by experience that a very durable and dense concrete molded product is produced having all air spaces removed, thereby rendering the product non-porous which is very important in road construction where blocks of this type are used. It has been found that by following this method wherein the blocks are produced under pressure so as to remove all air voids, 10 a block having a maximum strength is provided which will not crack, is frost proof, and will automatically take up expansion and contraction in the joints. 5

This invention constitutes an improvement on 15 my previous Patent #1,707,574 relating to a Roadway with improved curbstone and gutter, issued April 2, 1929, and is adapted to be constructed with the machine of a type illustrated in my previous Patent #1,927,717 dated September 19, 1933, 20 relating to a Block forming mold.

Having described the invention, what I claim is: 25 A landscape pavement comprising a plurality of rectangular paving blocks, a foundation of soil supporting the blocks, each block having an elongated inwardly extending channel upon the side thereof extending from a point near the top of the block to a point near the bottom thereof, the blocks being spaced from each other along their upper and lower edges to provide elongated vertically extending soil-receiving pockets between the blocks communicating with the channels in the blocks thereby providing seedling-receiving recesses between the blocks within which seedlings 30 take root and thrive in this manner providing a decorative joint between the blocks, the spacing of the blocks along their upper and lower edges providing a moisture-feeding medium from above the blocks and also from the foundation of soil 35 below the blocks to the spaces between the blocks 40 whereby the roots of the seedlings may draw moisture from the soil below the blocks, the soil between the blocks and the roots of the seedlings providing a tying medium to tightly hold the blocks together, each block having a rounded upper face and rounded side edges, the highest point in the upper face of each block being at its 45 approximate center to support traffic passing thereover away from the edges of the blocks to prevent tipping of the blocks and choking of the 50 seedlings under the weight of traffic passing thereover and to protect and preserve the seedlings against the wear of traffic. 55
